UNITED STATES PATENT OFFICE.

WEBSTER C. ESTES, OF FLATBUSH, NEW YORK.

DESIGN FOR A BOX.

SPECIFICATION forming part of Design No. 19,418, dated November 12, 1889.

Application filed October 19, 1889. Serial No. 327,579. Term of patent 7 years.

To all whom it may concern:

Be it known that I, WEBSTER C. ESTES, a citizen of the United States, residing at Flatbush, in the county of Kings and State of New

5 York, have invented and produced a Design for a Wooden Box, of which the following is a specification.

In the drawing the design of my box is represented by an elevation. The general shape 10 of this box is circular. The top has a crowning center A, and around the same are the ribs B C and cove D, and there is a rib E near

the center of the box, and the sides of the box are slightly tapering, and the bottom has a base-rim G and cove H, the whole forming a 15 neat and artistic design, as represented.

What I claim is—

The design for a box as herein shown and described.

Signed by me this 12th day of October, 1889. 20
WEBSTER C. ESTES.
